UNITED STATES PATENT OFFICE.

GUSTAV SOEDING, OF PHILADELPHIA, PENNSYLVANIA.

COIN-CONTROLLED STRENGTH-TESTER.

SPECIFICATION forming part of Letters Patent No. 399,942, dated March 19, 1889.

Application filed October 15, 1888. Serial No. 288,150. (No model.)

To all whom it may concern:

Be it known that I, GUSTAV SOEDING, a citizen of the United States, residing at Philadelphia, in the county of Philadelphia and State of Pennsylvania, have invented certain new and useful Improvements in Coin-Controlled Strength-Testers; and I do hereby declare the following to be a full, clear, and exact description of the invention, reference 10 being had to the accompanying drawings.

This invention relates to that class of apparatus designated as "strength-testers," or "dynamometers," and has for its object the provision of a construction whereby a single 15 machine will serve to register the amount of pounds pressure persons can exert by hand, either in pulling, pushing, or gripping, each of these ends being attained independently of each other and without in any way 20 changing the arrangement of its mechanism to accommodate it to either of the above-enumerated functions, the operation of the machine being dependent upon the dropping of a coin of a certain predetermined denomination into a suitable receptacle therefor 25 provided.

As heretofore constructed, machines of this class have been all provided with circular scales or dials with hands or pointers operating in conjunction therewith for registering the strength of muscular power exerted by the operator on the handles thereof. My invention provides a registering device in the 30 form of an upright tube or pipe with the figures arranged one above another, instead of in a circle, and the scale being in full view of the operator, so that he can see how far he has forced the indicator, and in view of this 35 feature can ascertain accurately the very utmost of his strength.

In gripping devices as heretofore constructed there have been provided stationary handles or bars with movable handles, &c., arranged relatively thereto, the stationary handles serving as a brace to rest the palm of the hand against, and the movable one being grasped by the fingers and a pulling action being imposed upon the said handle. My invention provides two movable handles, one 40 within the other, and being actuated each by

the other, but moving in opposite directions, so that if one be drawn outwardly the other will be forced inwardly. Therefore, if both be grasped by the hand, the inner handle by the fingers and the outer by the thumb and 55 palm, a perfect gripping effect will result.

My invention therefore consists in the combination, in a strength-tester or dynamometer, of two movable handles, one within the other and moving in opposite directions, with mechanism of peculiar construction for disclosing the amount of muscular power exerted in the act of pulling, pushing, and gripping; also, in the peculiar arrangement and combination of parts, as hereinafter fully described and 60 claimed.

Referring to the accompanying drawings, Figure 1 is a side elevation of my invention complete. Fig. 2 is a rear view with door removed, the upper and lower parts being broken 70 away. Fig. 3 is a front view, partly broken away. Fig. 4 is a detail of pulling and pushing racks and pinion. Fig. 5 is a detail perspective view of the coin-actuated lever, enlarged. Fig. 6 is a detail of modification of 75 registering device.

A is the inclosing case, in the form of a keg or small barrel, and mounted on a stand, B, which stand is bolted or otherwise secured to the floor by means of its enlarged or flaring 80 base. As will be noted, this case or barrel is formed with a bung-hole opening, a, for the reception of the lower end of the stand-pipe or indicator-tube C. Opposite the hole a, and cast integral with barrel A, is an elongated 85 boss, a', which is screwed or otherwise secured in the base or stand B.

D is the pulling-handle, of stirrup form, and secured on the end of a square spring-encircled rod, d, this rod passing through an opening in the head of the case A, and terminating at its inner end in rack d'. This rack d' 90 engages with pinion e, cast with the grooved wheel E, and is supported by the upright E', in which it slides.

Midway between the ends of the rod d is a collar, d², provided with a shoulder, d³, on its upper edge for engagement with the end or head f of the locking-bar F. The collar d² is bolted to the rod d and receives the impact of 95 100

one end of the helical spring G, the other end pressing against the inner side of the barrel-head a^2 . When handle D is drawn outwardly, or the handle I pressed inwardly, the effect 5 is the rotation of the wheel E and the pinion e.

In the groove of the wheel E runs a cord or belt, h, which passes over idler h', thence over pulley c, near the top of stand-pipe C, and down to the indicator H, where it is fastened 10 to an eye on one end of the indicator, the other end of the cord being similarly secured. This indicator is in the form of a straight piece of metal with eyes or loops in each end, and in the face or front of the metallic piece 15 is screwed or otherwise secured a finger or pointer, h², for registering with the figures on the plate c' and indicating the amount of pounds pressure exerted on the handles.

When, as above remarked, the rod d is 20 moved outwardly against resistance of the helical spring G, the wheel E will rotate, thereby causing the belt h, with the indicator H, to rise toward the top of the pipe C, thus correctly registering with the figures on the front 25 thereof and immediately dropping to its normal position, when the pulling action is released, owing to the reverse action of the spring G. The wheel E, as shown, is secured on a shaft, e', which shaft is journaled in 30 bosses e² on the inner sides of the case on screws passing through said case and into the ends of said shaft. The handle I, which is of U form, passes through openings in the head of the case A, bending upwardly and terminating 35 in racks i, which engage with pinions K on bosses k.

Branching out from each side of the collar d² is an arm, d⁴, which extends for a short distance toward the sides of the casing A, then 40 dropping downwardly a short distance and again bending toward the rear of the apparatus and terminating in racks d⁵, which engage with pinions K on the opposite sides from that of racks i, so that, as will be readily observed, 45 any movement of handles D will, through pinions K, actuate handle I in the reverse direction, and vice versa. At the same time the registering device will be operated by means of the wheel E and the pinion e and the belt 50 h, thus attaining the desired end and affording a perfect gripping action. This arrangement will also permit the independent operation of either of the handles D and I, the registering mechanism operating in either 55 case.

L is the coin-actuated lever, fulcrumed on a pin, l, in hanger l'. As will be observed, this lever is pivoted near its rear end, so that the weight of a single coin imposed upon its opposite end will depress said end, causing its rear end to rise and carry with it, through the medium of a connecting-bar, f', the locking-bar F, which locking-bar is pivoted on a pin, f², in a boss or lug, f³. This raising of the 60 locking-bar will permit of the pulling out of the handle D for any distance, and when the pulling action ceases said handle with its bar d

will be forced back by the spring G to its normal position. The beveled edge of the head f of the lever F permits collar d to slide easily 70 to the rear of said head f, thereby automatically locking itself.

As shown in Fig. 5, the end of the lever L which receives the coin is formed with an enlarged flat portion, M, in which is a circular opening, m, of slightly smaller diameter than that of a coin, preferably a five-cent piece, so that a coin, after being dropped into the slot n and passing through conveyer N, will rest edgewise in this circular opening. It will also 80 be noted that the lower end, n', of the conveyer N extends through the circular opening and for a short distance below the same, thus slightly tilting the coin and holding it so until the lever L has begun to drop, and by the 85 time the lever L has completed its downward movement the coin will have assumed a flat position on the part M. Thus it will be in position to be easily displaced, which displacement is accomplished through the medium of a bent wire, d⁶, which is secured to the rod d and strikes against the pin f⁴ in the end of the lever L, thus jarring said lever and causing the coin to fall into the bottom of the case or barrel A, from whence it can be removed at will by removing the back or door O, which is held in place by lugs or otherwise. This door may be of any desired form, and need not be further described.

In Fig. 6 of the drawings I have shown a 100 modification of the registering device, in which I have substituted a toothed wheel, P, with a pinion, p, to engage with the rack d' on the pulling-bar d. This construction can be used in place of the hereinbefore-described cord 105 and pulleys. The perpendicular rack-bar p' has at its upper end a pointer, h², for registering purposes. If found desirable, I may place a spiral spring on each of the arms i of handle I, instead of the single spring G on the 110 pull-bar d, thus employing a pair of springs instead of one spring. The bar d would in that event operate in the same manner and as effectually as in the first instance, only that this bar would be indirectly acted upon 115 by the springs.

The hereinbefore-described construction affords a device perfectly adapted for the purposes for which it is intended, needing no attention whatever and being always ready for 120 use, there being no manipulation of any of its parts necessary previous to such use. When either of the handles have been released, the indicator will immediately drop to zero-point and the bars assume their normal 125 position and automatically lock themselves and cannot be withdrawn or otherwise operated until a coin is placed in the slot, as described.

Having fully described my invention, what 130 I claim as new, and desire to secure by Letters Patent, is—

1. In a coin-controlled strength-tester, the combination of the two movable handles, one

within the other and moving in opposite directions in a parallel plane, a helical spring resisting the movement of the handles, a pair of gear-wheels, racks connected with the handles and transmitting their motion to the wheels, a registering device, and intermediate mechanism controlling the registering device, as and for the purpose set forth.

2. In a coin-controlled strength-tester, the combination of the movable handles, one within the other, a helical spring resisting the movement of the handles, a registering device consisting of a straight vertical scale and a vertically-moving pointer, the gear-wheels and mechanism intermediate the gear-wheels and the register, and racks connected with the said handles, whereby the amount of muscular strength exerted on said handles is indicated, as and for the purpose set forth.

3. In a coin-controlled strength-tester, the combination, with the handle D and the handle I, having the rack *i* and the pinion K, of the grooved wheel E and the shaft *e'*, the pinion *e* on said shaft, the idler *h'*, the pulley *c*, the cord *h*, and the indicator *H h²*, all combined for operation substantially as described.

4. In a coin-controlled strength-tester, the combination, with the handle D, having the spring-encircled rod *d*, the rack *d'*, the arms *d¹*, and the racks *d²* thereon, the handle I, having the racks *i* thereon, the pinions K and *e*, and the conveyer N, of the bent wire *d⁶*, secured in the rod *d*, the pin *f⁴*, the lever L, pivoted on

the pin *f⁴*, and the receiver M on said lever L, whereby the wire *d⁶*, striking the pin *f⁴*, will jar the coin off the receiver, as and for the purpose set forth.

5. In a coin-controlled strength-tester, the combination, with the handle D, having the spring-encircled rod *d*, the racks *d'*, the arms *d¹*, and the racks *d²*, the handle I, having the racks *i*, and the pinions K and *e*, engaged by said racks, of the coin-lever L, provided with the ring M, the coin-conveyer N, the said conveyer and ring operating to change the coin from a perpendicular to a horizontal position on said ring, as and for the purpose set forth.

6. In a coin-controlled strength-tester, the combination, with the case A, of the handles D and I, the rod *d*, the helical spring G on said rod, the collar *d²*, carrying the forked arms *d³*, the racks *d³*, *i*, and *d'*, shaft *e'*, journaled in the bosses *e²* and carrying the pinion *e*, and the wheel E, the cord *h*, the idler *h'*, the pulley *c*, the indicator *H h²*, the pipe C, the conveyer N, the lever L, the ring M, the hanger *l'*, the locking-bar F, having the head *f*, the bar *f'*, the wire *d⁶*, the pin *f⁴*, and the upright *E'*, all combined and arranged for operation substantially as described.

Signed this 11th day of October, A. D. 1888,
at the city of Philadelphia, Pennsylvania.

GUSTAV SOEDING.
